UNITED STATES PATENT OFFICE.

DEANE A. CABOT, OF BOSTON, MASSACHUSETTS.

DRILLING MACHINE.

Application filed June 16, 1921. Serial No. 478,117.

My invention relates to drilling machines and particularly to one having a fluid operated means for moving the drilling instrumentality relatively to the work.

5 My invention will be best understood from the following description with accompanying drawings of a specific embodiment of my invention selected for illustrative purposes, while the scope of my invention will 10 be more particularly pointed out in the appended claims.

In the drawings:

Fig. 1 shows in elevation a breast stopper embodying my invention;

15 Fig. 2 is a central longitudinal section on an enlarged scale of the feed cylinder and associated parts;

20 Figs. 3 and 4 respectively are sections on the lines 3—3 and 4—4 of Fig. 2;

25 Fig. 5 is a central longitudinal section on an enlarged scale through the upper end of the piston rod and associated parts;

30 Fig. 6 is a fragmentary section on the line 5—5 of Fig. 5;

35 Figs. 7, 8, 9 and 10 respectively illustrate in a more or less diagrammatic manner the operation of the controlling valve, each of these figures showing sections on the lines a—a and b—b of Fig. 6.

40 Referring to the drawings, I have shown a drill bit 1 operated by a drill bit actuator 3, the latter being of any suitable or usual type and as indicated one actuated by fluid pressure. The actuator 3 is carried in slid- 45 able relation to the feeding device indicated in its entirety at 5, this device having the rearwardly extending movable member 7 and connected portion 9, the latter being attached to the actuator in order that operation of the feeding device will move the latter.

45 As illustrated the feed cylinder comprises a cylindrical tube 11, which may be formed of a length of commercial stock, and sur- 50 rounding the feed cylinder at opposite ends thereof are rings 13 secured to the feed cyl- 55 inder in any suitable manner, as for ex- ample by welding. The front and rear cyl- 60 inder heads 15 are each provided with a re- 65 duced diameter portion 17 which enters the bore of the tube 11 and provides a shoulder 19 which abuts the end thereof. The cyl- 70 inder heads may be secured in any suitable manner and as shown I have provided for this purpose bolts 21 extending through the 75 perforated ears 23 formed on the cylinder

head and the perforated ears 25 formed on the rings 13.

Supported by the rings I herein provide a pair of parallel longitudinally extending members 27, these members and the rings being fixed to each other to form a single member formed as a unitary casting. Each member 27 is recessed to provide a slot 29 extending longitudinally throughout the 60 length of the member which slot receives the guides 31 supporting the drill bit actuator. Although these guides may be made integral with the casing of the drill actuator, I have shown them as part of the cradle 33, said cradle being provided at opposite 65 ends with pairs of perforated ears 35 which receive the lower pair of four side bolts 37 holding the sections of the drill actuator in assembled relation. As the specific nature 70 of the drill bit actuator and the cradle do not form part of my present invention the 75 same will not be further described.

Supporting the machine I herein provide a suitable means for attachment to a mine 80 column, a tripod or the like and as shown in the drawings this is exemplified by the trunnion 39. Integrally formed with the trunnion are a pair of rings 41 which surround and slidably engage the feed cylinder 85 tube 11. For preventing relative rotation between the trunnion and the cylinder and for transmitting the stresses occasioned by the drill actuator directly to the trunnion I provide each ring at its upper portion with a pair of upstanding portions providing flat 90 surfaces 43 in sliding contact with the lon- 95 gitudinally extending surfaces 45 formed on the lowermost portion of each of the mem- bers 27. It will be noticed by this means the trunnion may be moved to different posi- 100 tions along the feed cylinder and is splined thereto to prevent relative angular move- 105 ment between the parts.

For clamping the trunnion in its adjusted 100 positions I herein provide a strap 47 passing partly around the cylinder 11 and located in the space between the rings 41. At each end the strap is bent to form a radial portion 49 provided with a perforation 51 receiving the bolt 53. Between the rings I form the 105 member supporting the trunnion with brackets 55, each provided with a perforation 57 for receiving the bolt. Screw-thread- 110 edly engaged with the bolt is a nut 59 by means of which the bolt head 61 may be

caused to draw the strap 47 and rings 41 tightly into engagement with the cylinder to prevent movement of the trunnion.

Slidably mounted in the feed cylinder and in fluid-tight engagement with the walls thereof is shown a piston 63 to which is connected the piston rod formed by the projecting members 7 and 9 heretofore referred to. These members herein comprise an outer tube 65 and an inner tube 67, the former communicating with the rearward end of the feed cylinder by means of a passage 69 formed radially through the wall of the tube adjacent its point of connection with the piston and the latter communicating with the forward end of the feed cylinder through a passage 71 formed through the end wall of the piston. The portions 7 and 9 of the rod are connected by a transverse portion 73 serving as a handle for manually sliding the drill bit actuator along the ways and the upper end of the portion 9 is connected to the drill bit actuator as shown in Fig. 4.

Referring to Figs. 1 and 5 I have shown the actuator provided with a projecting valve casing 75 to which is connected the air hose connection 77 for conveying compressed air for operating the actuator and the feeding mechanism. On the rearward side of the valve casing I provide a socket 79 into which is screwed a nipple 81 having the frusto-conical recess 83 for receiving the correspondingly shaped end 85 of the rod 65, the latter being provided with a collar 87 forming a shoulder engaging the flange 89 of the union nut 91 and the latter screw-threadedly engaging the nipple to draw the end 85 into the socket. The forward face of the nipple fits the bottom of the socket in a fluid-tight manner and has formed therein the circular groove 93 which communicates with the passage 95 leading to the valve and with passages 97 leading to a circular groove 99 formed in the surface of the recess 83. The end portion 85 of the tube 65 is provided with radial passages 101 which when the device is assembled communicate with the groove 99 so as to place the interior of the tube 65 in communication with the valve casing. The upper end of the tube 67 I have shown supported in the bushing 103 carried by the end of the tube 65 and the other end of the tube 65 in a similar bushing 104 located forwardly of the opening 69 of the rod 65. The interior of the tube 67 communicates with the interior of the nipple the latter of which is placed in communication with the valve casing by means of a passage 105 located in the same plane as the passage 95.

In the valve casing 75 is mounted the controlling valve 107 which is of the frusto-conical turning plug type and is provided with an operating handle 109 and is provided with an internal conduit 111, main-

tained in constant communication with the air hose connection 77 in a manner readily understood by those skilled in the art. In the same plane as the passages 95 and 105 the valve is provided with a radial passage 113 and an arcual groove 115, the ends of the groove being spaced angularly a distance greater than that between the remote sides of the passages 95 and 105 and the passage 113 being of angular extent less than the angular distance between the adjacent sides of these passages. Placing the groove 115 in constant communication with the atmosphere is a passage 117 formed through the valve casing. Longitudinally and angularly spaced from the passage 113 is a second radial passage 119 adapted to be moved into and out of communication with the passage 121 supplying actuating fluid for operating the drill bit actuator and angularly spaced from the passage 119 and in the same plane therewith is a second radial passage 123.

The operation of the controlling valve is best indicated by Figs. 7, 8, 9 and 10. When the valve is in the position illustrated by Fig. 7, the supply of motive fluid to the actuator and each tube is interrupted and likewise is the communication between the tubes and the atmosphere. If the valve is moved clockwise or counterclockwise from the position illustrated by Fig. 7, respectively to those illustrated by Figs. 8 or 10, one or the other of the passages 95 and 105 will be placed in communication with a source of motive fluid supply by means of the passage 113 of the valve, while the remaining passage will be placed in communication with the atmosphere by means of the groove 115 and passage 117. As shown by Fig. 8, the passage 95 is supplied with motive fluid and the passage 105 is connected to the atmosphere and this admits motive fluid to the rearward end of the feed cylinder and vents the forward end of the feed cylinder which causes the feed piston to move the drill bit up to the rock. When the valve is moved to the position shown by Fig. 10, the supply and venting of the feed cylinder is the reverse of that when the valve is in the position of Fig. 8 and the piston will retract the drill bit from the rock. When the valve is in either of the positions just mentioned, the drill bit actuator may be supplied with motive fluid or said supply may be interrupted, for example, in the position shown by Fig. 8, if the valve is turned slightly in a counterclockwise direction, the passage 119 will be placed in communication with the passage 121, which will cause the drill bit to be actuated and at the same time the other conditions established by the valve in the position shown by Fig. 8 will remain uninterrupted. Similarly, if the valve is in the position in Fig. 10 and it is moved slightly in a clockwise direction, the passage 123 of the

valve will supply motive fluid to the passage 121 to supply the drill bit actuator without interrupting the supply to the feed cylinder or the venting thereof established by the 5 valve in said position.

If desired, the valve may be normally maintained in a position slightly counter-clockwise of the position shown by Fig. 9 instead of in the position shown by Fig. 7. 10 Under the conditions established by the valve in the position shown by Fig. 9, both ends of the cylinder are vented by means of the groove 115, which condition permits the feeding to be done manually, and 15 at the same time motive fluid is supplied to the passage 121 through the passage 119 to cause the actuator to operate. If the valve is moved slightly counter-clockwise from this position the supply to the actuator is interrupted while still maintaining the venting of both ends of the cylinder. This 20 enables the operator to move the bit up to the rock and manually operating the feed to spot the hole after which operation the valve 25 may be moved either to the position shown by Fig. 8 to cause the drill bit to be fed by fluid pressure or to a position intermediate that shown by Figs. 8 and 9 to cause it to be fed by fluid pressure with the drill bit 30 actuating. After the hole is drilled to the depth desired the valve may be turned further in a clockwise direction to the position shown by Fig. 7 to stop the operation of both the actuator and the feed or turned 35 further in a clockwise direction to the position shown by Fig. 10 to cause the drill bit to be retracted from the hole. If during the retracting operation the drill bit should 40 stick and it should be necessary to put the actuator into operation, the valve can be moved slightly in a clockwise direction from the position shown by Fig. 10 which will 45 cause the actuator to operate while the bit is being retracted.

The invention disclosed in this application constitutes an improvement on the inventions of George H. Gilman disclosed in his applications Serial Nos. 442,094 and 471,562, respectively filed February 3, 1921 and May 50 23, 1921.

Although I have described one specific embodiment of my invention for purposes of illustration it is to be understood that wide deviations may be made therefrom 55 without departing from the spirit of my invention.

Claims—

1. A machine of the character described having in combination a drill bit actuator, 60 a stationary feed cylinder formed of a length of tubing, a member having spaced parallel longitudinal portions forming spaced ways for slidably supporting said actuator and having transverse portions integral with and connecting said ways, said

transverse portions being formed to conform to the surface of said tubing and secured thereto by welding, a feed piston in said cylinder secured to said actuator for sliding the latter relatively to said cylinder, and a 70 part for connecting said machine to a support.

2. A machine of the character described having in combination a drill bit actuator, a stationary feed cylinder formed of a length 75 of tubing, a member having spaced parallel longitudinal portions forming spaced ways for slidably supporting said actuator and having transverse portions integral with and connecting said ways, said transverse 80 portions being formed to conform to the surface of said tubing and secured thereto by welding, a feed piston in said cylinder secured to said actuator for sliding the latter relatively to said cylinder, and a part for 85 connecting said machine to a support slid- able relatively to said cylinder between its ends.

3. A machine of the character described having in combination a drill bit actuator, a 90 stationary feed cylinder formed of a length of tubing, a member having spaced parallel longitudinal portions forming spaced ways for slidably supporting said actuator and having transverse portions connecting 95 said ways, said transverse portions being at the sides of said ways opposite said actuator and being formed with perforations through which said tubing is inserted, said perforations conforming to the surface of said tubing and said tubing being welded to said transverse portions, a feed piston in said cylinder secured to said actuator for slid- 100 ing the latter relatively to said cylinder, and means for connecting the machine to 105 a support.

4. A machine of the character described having in combination a drill bit actuator, a stationary feed cylinder formed of a length of tubing, a member having longitudinal 110 portions forming spaced ways for slidably supporting said actuator and having trans- 115 verse portions connecting said longitudinal portions, one of said transverse portions being in the form of a ring at the under side of said longitudinal portions at one end thereof, an end of said tubing being inserted through said ring, a head for said cylinder at that end thereof which is inserted through said ring, and bolts connecting said head and ring for drawing said head toward 120 said ring.

5. A machine of the character described having in combination a drill bit actuator, a stationary feed cylinder formed of a length 125 of tubing, a member having longitudinal portions forming spaced ways for slidably supporting said actuator and having trans- 130 verse portions connecting said longitudinal portions and situated at the end portions

thereof, said transverse portions conforming to the surface of said tubing, and a part for connecting said machine to a support sliding longitudinally of said cylinder between said transverse portions.

6. A machine of the character described having in combination a drill bit actuator, a stationary feed cylinder formed of a length of tubing, a member having longitudinal portions forming spaced ways for slidably supporting said actuator and having transverse portions connecting said longitudinal portions, one of said transverse portions being in the form of a ring at the under side of said longitudinal portions at one end thereof, an end of said tubing being inserted through said ring, and a head for said cylinder attached to one of said transverse portions by means for moving said head longitudinally of said cylinder.

7. In a machine of the character described, a tubular feed cylinder, means providing a way and carried by said cylinder, a member providing for attachment to a support and surrounding said cylinder said member slidably engaging said means, and means for clamping said member to said cylinder.

8. In a machine of the character described, a tubular feed cylinder, a member providing ways, said member being spaced from said cylinder intermediate its ends and its ends being carried by said cylinder, and a member providing for attachment to a support and being slidably carried by said cylinder intermediate the ends of said first named member.

9. In a machine of the character described, a tubular feed cylinder, a member providing ways, said member being spaced from said cylinder intermediate its ends and its ends being carried by said cylinder, a member providing for attachment to a support and being slidably carried by said cylinder intermediate the ends of said first named member, and means for securing said second named member in adjusted position.

10. In a machine of the character described, a tubular feed cylinder, a member providing ways, said member being spaced from said cylinder intermediate its ends and its ends being carried by said cylinder, a member providing for attachment to a support and being slidably carried by said cylinder intermediate the ends of said first named member, and means provided by said first named member for preventing rotation of said second named member relatively to said cylinder.

11. In a machine of the character described, means providing a way for a drill actuator, a cylindrical member carrying said means and adjustably supporting a second member for movement along it, said second member providing for attachment to a support for the machine, and said first named

means and said second member being in sliding contact to prevent angular movement of said second member on said cylindrical member.

12. In a machine of the character described, a feed cylinder, a member providing a way and carried by said cylinder in spaced relation thereto, and a member providing for attachment to a support slidably carried by said cylinder and contacting said first named member.

13. In a machine of the character described, a feed cylinder, a member providing a way and carried by said cylinder in spaced relation thereto, and a member providing for attachment to a support slidably carried by said cylinder and contacting said first named member, and means for securing said last named member in adjusted position.

14. In a machine of the character described, means for attaching the machine to a support, a member providing a slidable support for a drill actuator, said means providing a slidable support for said member, a feed cylinder for said drill actuator attached to said member, said first named means including a clamp for securing the same to said cylinder.

15. In a machine of the character described, a member having ways for slidably supporting a drill actuator, a tubular feed cylinder carrying said member, and means comprising a member separate from said first named member and directly carried by said cylinder for attaching said cylinder to a support for said machine.

16. In a machine of the character described, a drill actuator, the spaced parallel members 27 providing ways for supporting said actuator, the transversely disposed ring members 13 integrally carried by the members 27 beneath the same at the ends thereof, the tubular feed cylinder 5 extending through and carrying the ring members 13, and a feed piston in said feed cylinder and attached to said actuator.

17. In a machine of the character described, a fluid operated drill bit actuator, a fluid operated feeding device for said actuator comprising a stationary cylinder and a movable piston, said actuator being mounted on said cylinder at the side thereof for sliding movement parallel to the axis of said cylinder, a connection between said actuator and said piston, said connection comprising a substantially U-shaped tube projecting from the rearward end of said cylinder arranged with its legs substantially in a plane including the axial lines of said cylinder and drill bit actuator, a separate tube carried internally of the first mentioned tube, said tubes being respectively in fluid communication with said cylinder at opposite sides of said piston, and a single valve

for controlling the fluid admitted to said actuator and each tube.

18. In a machine of the character described, a fluid operated drill bit actuator, a fluid operated feeding device for said actuator and comprising a stationary cylinder and a movable piston, said actuator being mounted on said cylinder at the side thereof for sliding movement parallel to the axis of said cylinder, a connection between said actuator and said piston, said connection comprising a substantially U-shaped tube projecting from the rearward end of said cylinder arranged with its legs substantially in a plane including the axial lines of said cylinder and drill bit actuator, a separate tube carried internally of the first mentioned tube, said tubes being respectively in fluid communication with said cylinder at opposite sides of said piston, and a single valve for controlling the fluid admitted to said actuator and each tube and operative first to cause movement of said piston and afterward to supply said actuator without interrupting said movement.

19. In a machine of the character described, a fluid operated drill bit actuator, a fluid operated feeding device for said actuator and comprising a stationary cylinder and a movable piston, said actuator being mounted on said cylinder at the side thereof for sliding movement parallel to the axis of said cylinder, a connection between said actuator and said piston, said connection comprising a substantially U-shaped tube projecting from the rearward end of said cylinder arranged with its legs substantially in a plane including the axial lines of said cylinder and drill bit actuator, a separate tube carried internally of the first mentioned tube, said tubes being respectively in fluid communication with said cylinder at opposite sides of said piston, and coordinated valvular means for controlling the fluid admitted to said actuator and each tube.

20. In a machine of the character described, a fluid operated drill bit actuator, a fluid operated feeding device for said actuator and comprising a stationary cylinder and a movable piston, said actuator being mounted on said cylinder at the side thereof for sliding movement parallel to the axis of said cylinder, a connection between said actuator and said piston, said connection comprising a substantially U-shaped tube projecting from the rearward end of said cylinder arranged with its legs substantially in a plane including the axial lines of said cylinder and drill bit actuator, a separate tube carried internally of the first mentioned tube, said tubes being respectively in fluid communication with said cylinder at opposite sides of said piston, and coordinated valvular means for controlling the fluid admitted to said actuator and each tube.

nated valvular means for controlling the fluid admitted to said actuator and each tube, and operative first to cause movement of said piston and afterward to supply said actuator without interrupting said movement.

21. In a machine of the character described, a fluid operated drill bit actuator, a fluid operated feeding device for said actuator and comprising a stationary cylinder and a movable piston, said actuator being mounted on said cylinder at the side thereof for sliding movement parallel to the axis of said cylinder, a connection between said actuator and said piston, said connection comprising a substantially U-shaped tube projecting from the rearward end of said cylinder arranged with its legs substantially in a plane including the axial lines of said cylinder and drill bit actuator, a separate tube carried internally of the first mentioned tube, said tubes being respectively in fluid communication with said cylinder at opposite sides of said piston, and a single valve having a position in which it is operative to exclude admission of motive fluid to both tubes and to said actuator and operative by movement thereof from said position to supply one of said tubes with motive fluid to the exclusion of the other and to connect said other to the atmosphere and under such condition at will to supply said actuator with motive fluid.

22. In a machine of the character described, a fluid operated drill bit actuator, a fluid operated feeding device for said actuator and comprising a stationary cylinder and a movable piston, said actuator being mounted on said cylinder at the side thereof for sliding movement parallel to the axis of said cylinder, a connection between said actuator and said piston, said connection comprising a substantially U-shaped tube projecting from the rearward end of said cylinder arranged with its legs substantially in a plane including the axial lines of said cylinder and drill bit actuator, a separate tube carried internally of the first mentioned tube, said tubes being respectively in fluid communication with said cylinder at opposite sides of said piston, and a single valve having a position in which it is operative to exclude admission of motive fluid to both tubes and to said actuator and movable therefrom in opposite directions selectively to supply either of said tubes to the exclusion of the other and connect said other to the atmosphere and under such condition at will to supply said actuator.

In testimony whereof, I have signed my name to this specification.

DEANE A. CABOT.
